UNITED STATES PATENT OFFICE.

EMIL L. LOESER, OF WATERTOWN, WISCONSIN.

GAME.

1,399,133.

Specification of Letters Patent.

Patented Dec. 6, 1921.

Application filed February 24, 1920. Serial No. 361,050.

To all whom it may concern:

Be it known that I, EMIL L. LOESER, a citizen of the United States, and resident of Watertown, in the county of Jefferson and State of Wisconsin, have invented new and useful Improvements in Games, of which the following is a description, reference being had to the accompanying drawings, which are a part of this specification.

10 The present invention relates to certain new and useful improvements in games and refers more particularly to a game played with a plurality of cards.

The primary object of the present invention is to provide a card game which will be instructive to the player and which indicates the manner in which a negative or destructive attitude of the mind may be overcome by a positive or constructive attitude of the mind.

Another object of my invention is to provide a card game comprising a plurality of sets of cards each having delineations thereon designating various attitudes or conditions of the mind with respect to the subject matter of the set.

A further object of the present invention is to provide a card game which will not only be of a constructive and educational nature, but will be extremely amusing to the old and young alike.

With the above and other objects in view which will appear as the description proceeds my invention resides in the novel construction, combination and arrangement of parts substantially as hereinafter described and more particularly defined by the appended claims, it being understood that such changes in the precise embodiment of the 40 herein disclosed invention may be made as come within the scope of the claims.

In the accompanying drawings I have illustrated one complete example of the physical embodiment of my invention constructed according to the best mode I have so far devised for the practical application of the principles thereof, and in which:

Figure 1 is a plan view of one of the positive cards of one of the sets or series comprising my game.

Fig. 2 is a plan view of one of the negative cards thereof.

Fig. 3 is a plan view of one of the master, or "Plan" cards thereof.

55 Fig. 4 is a plan view of the other master, or "Over the top" card thereof.

Fig. 5 is a plan view of one of the positive cards of another of the series of cards comprising the complete set.

Fig. 6 is a plan view of the negative card 60 thereof.

Fig. 7 is a plan view of one of the master, or "Plan" cards thereof, and

Fig. 8 is a plan view of the other master, or "Over the top" card thereof.

My game comprises a plurality of series of cards designating several compartments representing different conditions of a person's life as the Home, Thought, Habit, Character, School, Success, Happiness, 70 Business and Neighbor, but as the subject matter of the cards of each series are substantially the same except that they refer to the specific condition as Home, Thought, Habit, etc., but two series have been shown 75 in the accompanying drawings.

Each series consists of six cards, two positive or constructive Thought cards 10 having delineations thereon representing a positive or constructive mental attitude, and two 80 negative Thought cards 11 having delineations thereon representing a negative or destructive mental attitude, and two Master cards 12 and 13 having delineated thereon the word "Plan" and "Over the top" respectively.

Figs. 1 to 4 designate cards of the "Home" department, and Figs. 5 to 8 inclusive designate cards of the "Thought" and each series as before stated comprises six cards, 90 and as the two cards of each series not shown in the drawings are merely duplications of the cards 10 and 11 depicted in Figs. 1, 2, 5 and 6 the same have not been shown in the drawings.

95 The main object of my game is the illustration to the player of how a negative or destructive attitude of the mind may be overcome by the better positive or constructive attitude and thus each card illustrates 100 some good moral to the player.

The game may be played by from two to four players and the cards of all the series are shuffled or mixed together and dealt one card at a time to each player until each one 105 has an equal number. Each player then arranges the cards of the same department together in order and in accordance with their importance in life, as the "Home", which is first, "Thought", which is second, 110 "Habit", which is third, "Character", which is fourth, "School", which is fifth, "Success",

which is sixth, "Happiness", which is seventh, "Business", which is eighth and "Neighbor", which is ninth, the cards of each series being numbered as at 14 to designate such importance.

- 5 The object of each player is to make as many points as possible and the cards are played with a view to mapping out or planning an order of living with regard to the 10 Home, Thought, etc., and each plan to be successful must end with both of the negative cards 11 thereof covered by their opposite or positive cards 10 and a plan of the cards of which were played so that one or 15 both of its negative cards 11 remain unmatched or uncovered, by the opposite or positive cards 10 will be considered unsuccessful only. This method of forming plans with respect to the various departments 20 represented by the series is worked out as follows:

- The player to the left of the dealer begins by playing a "Plan" card 12 of any one of the series, and in turn is followed by 25 the player to his left with either a negative card 11 or a positive card 10 of the same department or order. The player who plays the first negative card 11 belonging to the department of which the "Plan" card 12 has 30 been played, will call out "Over the top" upon which the holder of the "Over the top" card 13 belonging to the same department will play this card. It is now the duty of the player to the left of the person playing 35 the "Over the top" card 13 to cover the negative card 11 with its opposite positive card 10 and if unable to do so must say "Pass" when it becomes the duty of the player to his left to cover the negative card 40 or say "Pass."

- When the player of the first negative card fails to call for the "Over the top" card and the player to his left holds a positive card of the same order or department, he has the 45 right to call for the "Over the top" card or he may cover the negative card with this positive card. If he calls for the "Over the top" card, his turn to play is forfeited and it is now the turn of the player to the left 50 of the person playing the "Over the top" card.

- After both negative cards have been played and the "Over the top" card has not yet been played the holder of the "Over the 55 top" card will take it unto himself to play this card without orders to do so. If in addition to the "Over the top" card he should also hold a positive card of the same order or department, he may first play the 60 "Over the top" card and then the positive card.

The points are scored in the playing of my game as follows:

When a player matches or covers a negative card with its opposite positive card of

of the same order or department, the player of the positive card scores one point. When both negative cards have been played and the "Over the top" card has not yet been called for, the holder of the "Over the top" 70 card scores one point by playing this card and if he also holds and plays a positive card of the same department and order he makes an additional point. The player who covers the second positive card with its opposite negative card thereby completing the game wins the plan and scores five points in addition to any other points he may make. 75

The points or credits are lost in the game when the player of the first negative card 80 fails to call for the "Over the top" card and his neighbor to his left plays the positive card, the player of the negative card loses one point. When the player or players to the left of the person playing the "Over the 85 top" card are unable to cover the negative card belonging to the department which is being played, each player who is compelled to pass loses one point. When one or both negative cards of a plan remain unmatched 90 and the plan falls through, the player of the "Plan" card loses five points.

The player who played the positive card which won the plan or played the last negative card by which the plan fell through, 95 will resume the game by playing another "Plan" card or being unable to do so will "pass."

As stated above, when a player is unable to play in his turn he will "pass," when the 100 player to his left will take his turn. Only one plan can be played at one time and cards belonging to other departments cannot be played until the "Plan" card of that particular department has been introduced in 105 the game. When all cards have been played the game ends and the player holding the most points or credits after deducting the points or credits lost wins the game.

Each player should bear in mind while 110 playing the game that a negative card represents a negative attitude of the mind and a positive card a positive attitude of the mind. As before stated the act of the player in covering a negative card with its opposite 115 positive card illustrates or symbolizes the mental action that takes place in the mind when a negative attitude of the mind is destroyed by its opposite positive attitude, or a negative thought destroyed by its opposite 120 positive thought.

What I claim as my invention is:

1. A game including a plurality of pairs of cards, one card of each pair having delineations thereon indicative of a destructive 125 mental attitude and the other card of each pair having delineations thereon indicative of the opposite or a constructive mental attitude, the cards indicative of a destructive mental attitude when played being 130

covered by a card indicative of a constructive mental attitude thus illustrating to the players how mental attitudes of one type or class may be counteracted by mental attitudes of the opposite type or class.

2. A game including a plurality of cards arranged in sets, the cards of each set including an introductory card and a plurality of pairs of cards, one card of each pair having 5 delineations thereon indicative of a certain state of mind or condition and the other card of each pair having delineations thereon indicative of a state of mind or condition opposite to that of the first mentioned card 10 of each pair, the cards indicative of one state of mind or condition being covered by cards indicative of the opposite state of mind or condition, respectively, thereby illustrating to the players how one state of mind or condition may be counteracted by an opposite state of mind or condition, one of said master cards serving to introduce the respective 15 sets of cards into the game, and the other of said master cards serving to bring into the game the card having delineations indicative of a state of mind or condition opposite to that of the card played prior to said last 20 mentioned master card.

3. A game including a plurality of cards

arranged in sets, the cards of each set including two master cards and a plurality of pairs of cards, one card of each pair having delineations thereon indicative of a certain state of mind or condition and the other card of each pair having delineations thereon indicative of a state of mind or condition opposite to that of the first mentioned card of each pair, the cards indicative of one state of mind or condition being covered by cards indicative of the opposite state of mind or condition, respectively, thereby illustrating to the players, how one state of mind or condition may be counteracted by an opposite state of mind or condition, one of said master cards serving to introduce the respective 40 sets of cards into the game, and the other of said master cards serving to bring into the game the card having delineations indicative of a state of mind or condition opposite to that of the card played prior to said last 45 mentioned master card.

In testimony whereof, I affix my signature.
EMIL L. LOESER
